UNITED STATES PATENT OFFICE.

ASA C. BAUM, OF LITTLE FALLS, NEW YORK.

NAPPER.

1,082,992.

Specification of Letters Patent. Patented Dec. 30, 1913.

Application filed February 26, 1912. Serial No. 679,950.

To all whom it may concern:

Be it known that I, ASA C. BAUM, a citizen of the United States, residing at Little Falls, in the county of Herkimer and State 5 of New York, have invented certain new and useful Improvements in Nappers, of which the following is a specification, reference being had therein to the accompanying drawing.

10 My invention relates to an improved napper, and I declare that the following is a full, clear, concise and exact description thereof, sufficient to enable one skilled in the art to make and use the same, reference 15 being had to the accompanying drawings, in which like reference characters refer to like parts throughout.

The invention relates particularly to a machine applicable for use in knitting mills 20 where the product is in the form of a tube, being knitted on a circular machine, and the invention consists in the various features shown, described and set forth in the drawings, specification and claims.

25 In the drawings Figure 1 is a full view of the napper; Fig. 2 is a plan view of the napper, taken on the line 2—2 of Fig. 1 and showing the mechanisms which raise the nap in position to operate on a tube 30 of a given diameter, while Fig. 3 is a like view, but with those parts in a different position—adapted to operate on a tube of lesser diameter; Fig. 4 is a partial view of the machine as shown in Fig. 2, but on a 35 larger scale; Fig. 5 is a sectional view of a portion of the machine, on the line 5—5 of Fig. 4; Fig. 6 is a view of parts of the machine shown particularly in Fig. 5 and looking at such parts shown in that figure 40 in the direction of the arrow; Fig. 7 is a detail view of a part of the machine, parts being broken away.

Referring to the figures in detail, A represents standards which support a frame 45 B which is in the form of a flat ring. C shows standards mounted on the ring and which support the bed D which is in the form of a ring. The shaft E is mounted in the frame, as in one of the standards C, 50 and carries suitable power transmitting members, represented by pulley F and F', and a beveled gear pinion G. A recessed ring 1 is bolted onto the bottom of the bed D. A beveled gear 2 is carried on the ring 1 by means of an outwardly projecting flange 3 which lies in a corresponding cut-

out in the ring 1. The gear 2 is in the form of a ring of the cross-section shown in Fig. 5, and on an inwardly extending flange 4 rests and is secured a ring 6 which is designed to be rotated on the bed D. The bed D has secured thereto a beveled gear 8. The ring 6 has radially disposed cutouts, three being shown in this machine, in which are placed blocks 10 which are adapted to be moved toward and from a common center. Mounted in each of these blocks is a shaft 12 which carries a beveled gear 14 adapted to mesh with the beveled gear or rack 8. The stud or shaft 12 is longitudinally 65 grooved and the gear 14 is formed with a corresponding projection fitting into said groove so that notwithstanding the inner and outer movement of the block 10, the gear 14 sliding along the stud or shaft remains in mesh with the gear or rack 8. It will be noted that the ring 6 is cut out, as indicated at 15, for the location of the gear 14. On the inner end of the stud or shaft 12 is mounted a gear 17 with which 70 meshes, one on each side, worms 18 and 19 which are mounted in block 10 and which project upwardly above the block and carry the heads 20 and 21 which are suitably clothed for the napping work, and which 75 it is seen revolve in opposite directions.

In the operation thus far described beveled gear pinion G causes the ring gear 2 to revolve, being supported on the ring 1 which is fixed to the stationary bed D. The revolving ring gear 2 carries with it the ring 6. The gear ring or rack 8 being fixed to the stationary bed D, the revolution of the rings 2 and 6 causes the revolution of shaft 12 by the mesh of its gear 14 with the stationary rack 8, and the revolution of the shaft 12 causes the worms 18 and 19 to rotate and correspondingly revolve the heads 20 and 21.

On each block 10 is fixed a pin 24. An adjusting ring 25 rests on the ring 6 (it being cut out for gear 14, as seen) and having a tangentially disposed cut 27 which receives the pin 24. At suitable points in the ring 6 is fixed a stud 28 which projects through slot 29 cut in the adjusting ring 25, 100 and a washer 30 and nut 31 are provided so that the adjusting ring 25 can be held in fixed position relative to the ring 6. By means of these mechanisms the adjusting ring, when loosened, may be moved a given 105 distance in either direction, so that by engagement of the pin 24 in the slot 27 each

of the blocks 10 may be synchronously moved toward or from the center of the machine to bring the napping members or heads 20 and 21 of each bar into engagement with the fabric.

At one side of the machine is located a pair of brackets, one being shown in Fig. 1 at 35. Each bracket projects from the machine and the two are formed to inclose feed 10 pipe 36. The feed pipe extends upwardly and has a semicircular turn and extends downwardly over the center of the machine, as seen in Fig. 1. At 38 the feed pipe has a vertical cutout which opens into horizontal 15 cutout 39, and the thumb-screw 40 engages the pipe in the slots so that the thumb-screw 40 may be loosened and the pipe may be raised and turned so as to be supported by the engagement of the thumb-nut in the 20 horizontal slot 39. This brings the member 45, to be described, and the portion of the pipe 36 which supports it, above and to one side of the napping members. When in such position the member 45 is removed. 25 A roll of cloth is supported adjacent the foot of the pipe, as on bar 41 supported in prongs 42 of the bracket 35. The end of the cloth is then passed up through the pipe and brought out at the upper depending 30 end which is at one side of the machine when the pipe is so raised. The end of the tube of cloth is then turned backward on the outside of the pipe and the entire roll of cloth is in that manner fed through the 35 pipe and turned backward on the outside so that it can be fed to the machine, as will be seen.

45 represents a drum of a given size. The size is to be determined according to the 40 size of the tube which is to be napped. The upper end of the drum fits into the upper depending end of the pipe 36 and is provided with a pin 46 which fits into a key-hole cutout 47 in the end of the pipe 36, so 45 that the drum of whatever size it may be can be fitted into and secured to the pipe 36, and thus the drum will receive the cloth as it is drawn down from the pipe and through the machine. In order to prevent the cloth 50 from being carried around the drum and so twisted by the action of the heads as they travel around the drum, I set into the drum at the top and the bottom small wheels 50 and 51 provided with suitable teeth 52 and 55 supported by their axes resting in blocks 53 suitably secured in proper places in the drum.

Near the bottom of the machine is a roller or take-up, indicated by 55, which is 60 revolved by means of gear or rope 56 carried by a pulley 57 on the shaft E and pulley 58 on the shaft 55.

In operating the machine a roll of cloth is passed inside the tube 36 and turned wrong 65 side out on the outside of the tube. The

tube being in place with member 45 centrally located relative to the brushes 20 and 21 the cloth is drawn off the tube onto roller 55 being napped as it passes over member 45 by the rotating brushes 20 and 21. By 70 the means described these brushes are caused to revolve and the entire set of brushes rotates around member 45. The brushes, as also set forth, may be adjusted to nap cloth of various sizes of tube being set, by means 75 of the adjusting mechanisms, at a greater or less distance from the center of the machine.

Having described my invention, what I claim as new and desire to secure by Letters 80 Patent, is;

1. A napper consisting of a frame, a gear ring mounted to revolve relative thereto, a ring connected to rotate with the former ring, a beveled gear supported in the latter 85 ring, a rack fixed to the frame and meshing with said gear, a longitudinally adjustable shaft supporting said gear and provided with a worm-gear and worms meshing with the worm-gear and provided with napping heads, whereby the revolution of the first-mentioned gear is transmitted to the said heads and the latter are adjustable inward or outward with the shaft.

2. A napper having a plurality of vertical 95 revolving napping members equi-distant from the center, a pipe mounted to receive a tube of fabric through the interior and to carry said fabric on the exterior of the pipe, a drum removably mounted on the pipe, the 100 pipe being mounted so as to position the drum in the center of the napping members.

3. A napper having a vertical pipe with its upper portion curved and depending and normally positioned in the center of the device, a drum removably mounted on the pipe and napper members mounted about the drum and equi-distant therefrom, and means for revolving the napping members about the drum.

4. A napper comprising vertically disposed revolving members, means supporting the said members, the said means being revoluble about the center of the napper, means connected with the former means whereby 115 to revolve the nappers on their centers in their revolution, a pipe adapted to receive a tube of fabric and to carry the same on the exterior thereof and a drum connected with the napper and with the pipe and adapted to 120 be carried at the central point between the said napper members.

5. In a napper, the combination of a revolving ring, blocks radially movable in said ring, a gear movably mounted on each block, 125 napping members operatively connected with the blocks and means operatively connected by the said blocks whereby to give them a synchronous radial adjustment.

6. In a napper, a fixed rack, a movable 130

ring, radially movable blocks in the ring with gears adapted to maintain engagement with the rack and means whereby to give the blocks identical radial adjustment.

5 7. In a napper, a feed-pipe mounted at one side of the machine and extending over the center of the machine in a depending removable drum and means whereby to hold the pipe in raised position with the drum at 10 one side of the machine.

8. In a napper, a series of napping members equidistant from a given center, a feed-pipe mounted at one side and bent over and downward above said center, a drum of 15 given diameter removably supported by the pipe and between the napping members and means whereby to adjust the said members in unison relative to the drum.

9. In a napper, a series of napping members equidistant from a given center, a feed-pipe mounted at one side and bent over and downward above said center, a drum of 20

given diameter removably supported by the pipe and between the napping members and means whereby to adjust the said members 25 in unison relative to the drum and means whereby to cause the said members to revolve.

10. In a napper, a series of napping members equidistant from a given center, a feed-pipe mounted at one side and bent over and downward above said center, a drum of given diameter removably supported by the pipe and between the napping members and means whereby to adjust the said members 35 in unison relative to the drum and means whereby to cause the said members to revolve and to revolve around the drum.

In testimony whereof I hereunto affix my signature in the presence of two witnesses. 40

ASA C. BAUM.
